UNITED STATES PATENT OFFICE

2,355,673

APPARATUS FOR COATING WEBS

Edward Person, Brooklyn, N. Y., assignor to General Felt Products Inc., a corporation of New York

Application July 22, 1940, Serial No. 346,717

4 Claims.

(Cl. 91—33)

This invention relates to an apparatus for coating a web of paper, textile material or the like.

One of the main objects of the invention is to provide an efficient and reliable apparatus for coating webs.

A further object of the invention is to effect the application of a double coating to a web in a satisfactory and efficient manner.

A further object of the invention is to insure that coating as applied to the web shall be smooth and free from blemishes.

A further object of the invention is to insure uniform thickness of the coating upon the web.

A further object of the invention is to effect the accurate and reliable adjustment of the thickness of the coating upon the web.

A further object of the invention is to so coordinate the regulation of the application of the coating to the web with the position of inspection of the applied coating, that the effect of the regulation upon the applied coating may be readily observed during the regulation.

A further object of the invention is to provide for the convenient and ready inspection of the applied coating.

Other and ancillary objects of the invention will appear hereinafter.

In the accompanying drawings which illustrate the invention—

Fig. 1 is a side elevation of apparatus embodying the invention of means and by which the method may be carried out;

Fig. 2 is a top plan view of the apparatus of Fig. 1, the feed roll being partly broken away and its support being partly in section;

Fig. 3 is a fragmentary detail, on an enlarged scale and partly in section, of means for adjusting one of the coating-applying rolls; and

Fig. 4 is a diagrammatic view of apparatus embodying the invention and by which the method may be practiced, adapted to the formation of laminated fabrics.

Referring to the drawings and first to Figs. 1 to 3 inclusive, the roll of paper, textile material or the like, which is generically referred to as the "web," is fixed to the rotatably mounted shaft 1 after the well known manner of mounting such rolls in connection with printing presses and the like.

From the roll the web 2 passes between idler rolls 3 and 4. These rollers 3 and 4 are provided for tensioning the web.

From the rollers 3 and 4 the web 2 passes over the top of the coating-applying roller 5, which is

heated sufficiently to maintain the coating in sufficient fluid or plastic condition for application to the web, thence over the chromium plated convex face 6 of a heated smoothing bar 7 having the electric heater 7', thence about the roller 8. The web thence passes about the roller 9 rotatably mounted adjacent the top of the frame. The roller 8 contacts the opposite side of the web from the coating and may be cooled or not as may be desired to expedite hardening of the coating. Such cooling may be unnecessary as the desired hardening may take place at atmospheric temperature in the course of the rather long passage from the smoothing bar 7 to the roller 9. The roller 9 is cooled to insure the hardening of the coating to the desired degree.

The roller 9 raises the web high in the air so that there is room for an operator to stand under it for the purpose of observing the coating on the inclined under side of the web, and the apparatus is divided at this point as shown so that there is room for the operator to sit in between the two halves of the apparatus. Also, as will appear hereinafter, controlling means for the apparatus is placed ready at hand for the operator from his position beneath the web to control the operation of the apparatus.

From the roller 9, the web with the solidified coating passes downwardly and beneath the idler roll 10. From the roll 10 the web passes over the roll 11 for applying a second coat of coating. From the roll 11 the web passes over the convex surface of the heated smoothing bar 12 which smooths the second coat similarly to the smoothing of the first coat by the smoothing bar 7 as already referred to.

From the smoothing bar 12, the web passes about the roller 13. From the roller 13 the web passes about the roller 14 and thence to the take-up reel 15 on which it is wound.

The tension rollers 3 and 4 are rotatably mounted in opposite ends of the arms 16, which arms are pivotally mounted at their mid points 17 in the upstanding brackets 18 in the machine frame base 19. Rollers 3 and 4 may be turned upon the center 17 to cause the path of the web about the rollers to be longer or shorter whereby the arcs of contact of the web with the rollers are increased and the slack in the web taken up, or the reverse, by rotating the arm 16 in one direction or the other by means of a hand wheel 20 fixed on the shaft 21 journaled in the bracket 18 and having fixed to it a spur gear 22 meshing with a spur gear 23 fixed on one of the rotatably mounted gudgeons 17.

When the rollers 3 and 4 are rotated about the center 17 (in a clockwise direction as viewed in Fig. 1) whereby the path of the web about the rollers is increased and the slack taken up, it will be apparent that the drag or brake on the web, and thus the tension on the web, will be increased, while a rotation of the rollers in the opposite direction will decrease such dragging effect and reduce the tension on the web.

From the rollers 3 and 4 the web passes about the top of the coating-applying roller 5. This roller 5 is rotatably mounted in bearing boxes 25 vertically slidably in the bracket 26 mounted on the machine frame base 19. Beneath the roller 5 is a roller 27 dipping into a bath 28 of molten coating, the coating being maintained molten by heating the bath in any well known or suitable manner. The roller 27 is rotatably mounted in the bearing boxes 29 vertically slidable in the bracket 26. However, the boxes 29 are maintained at their lowermost points by reason of gravity and compression springs 30, one such compression spring being mounted between the boxes 25 and 29 at each end of the rollers, such springs tending to force the boxes, and therefore the rollers, apart.

The rollers 5 and 27 are geared together by the pairs of spur gears 30' at the ends of the rollers.

Each of the bearing boxes 25, and therefore the roller 5, is forced downwardly against the pressure of the springs 30 by means of a screw-threaded shaft 31 bearing at its end against the box 25 in screw-threaded engagement in a sleeve 32, the thread on the shaft 31 and the interior of the sleeve 32 being relatively coarse, the sleeve being threaded at its exterior upon the interior of a projection 33 fixed upon the bracket 26, the thread between the projection 33 and the sleeve being fine with relation to the thread on the shaft 31. To the upper end of the shaft 31 is fixed a hand wheel 34 by means of which the shaft 31 may be turned in one direction or the other, when the shaft 31 will be moved downwardly, forcing the boxes 25 downwardly, and with it the roller 5, against the pressure of the springs 30, or when the wheel 34 is turned in the opposite direction, the shaft 31 will be moved upwardly, thus permitting the boxes 25 and their carried roller to rise under the action of the spring 30.

By turning the sleeve 32 in one direction or the other in the projection 33, the sleeve will be moved upwardly or downwardly and the shaft 31, boxes 25 and roller 5 will be moved accordingly, or by reason of the fact that the thread on the outer surface of the sleeve 32 is finer than the thread on the shaft 31, a finer adjustment may be made than by turning the shaft. The desired adjustment of approach of the rollers 5 and 27 may, therefore, be roughly adjusted by turning the wheel 34 in one direction or the other and then the nicer and final adjustment may be accomplished by turning the sleeve 32. The two ends of the roller 5 would ordinarily be adjusted to approximately the same distance from the ends of the roller 27 by means of the hand wheel 34 at either end of the roller. The adjusting means at both ends of the roller is accomplished by the operation of either hand wheel, by reason of the fact that the two hand wheels are connected in driving relation by means of sprocket wheels 35 fixed upon the respective shafts 31 and joined in driving relation by a sprocket chain 36.

To effect the finer adjustment by turning the sleeves 32 as before referred to, each sleeve has fixed upon it a sprocket wheel 37 drivingly connected by a sprocket chain 38 with a sprocket wheel 39 rotatably mounted in the bracket 26 and having fixed to it a hand wheel 40, so that by turning the hand wheel 40 in one direction or the other, the sleeve 32 is turned in one direction or the other and the finer adjustment of the shaft 31, as referred to, is accomplished.

The hand wheels 34 are at opposite sides of the machine so that they can be simultaneously adjusted by an operator from either side, but it will be noted that there is a wheel 40 for each end 15 of the upper roll whereby the finer adjustment of the ends of that roll may be independently accomplished. This does not result in inconvenience because both hand wheels 40 are within 20 convenient reach of the operator when he is beneath the web 2, where he would ordinarily stand to inspect the coating, and moreover, due to irregularities, or for other reasons, one end of the roller may require a slightly different adjustment from the other in order to effect the desired 25 result.

The lower roller 27 is driven in the direction of the arrow by means of an electric motor 41 having a sprocket wheel 42 on its shaft, which sprocket wheel is drivingly connected by means 30 of a sprocket chain 43 with a sprocket wheel 43' fixed on the shaft of the roller 27, the upper roller 5 being driven through the pair of spur gears 30'.

The thickness of the coating applied to the 35 web may be regulated by regulating the space between the rollers 5 and 27, which space can be regulated by means of the hand wheels 34 and 40 as described. The movement of one roller 40 away from another in such adjustment will, however, be very slight so that the gears connecting the rollers will maintain their engagement at all times.

The smoothing bar 7 should have an extremely 45 smooth and hard surface for bearing against the web. This may be effected by chromium plating such surface. This smoothing bar is fixed to a shaft 44 which is rotatably mounted in the frame at 45 and 46. To turn this shaft, there is fixed upon it a worm wheel 47 engaging with a worm 50 48 fixed upon a shaft 49 rotatably mounted in the frame of the machine and having fixed upon it the hand wheel 50 conveniently operated by an operator standing beneath the high portion 55 of the web passing through the apparatus. By means of the wheel 50 the smoothing bar 7 may be turned about its axis and be made to have a greater or less pressure upon and area of contact with the web whereby its effect upon a coating can be regulated, and it will be obvious that this 60 can be done by an operator from a position beneath the web passing between the rollers 9 and 10 where he can observe the condition of the coating.

Passing from the smoothing bar 7 the web 65 passes about the roller 8, with the coating side out, the roller 8 being rotatably mounted in the frame, and from the roller 8 the web passes to the highly elevated roll 9 during which passage the coating has an opportunity to solidify which it does to an extent making it permissible for the coating to come against the roller 9 which is preferably cooled in order to insure proper hardening or setting of the coat.

From the roller 9 the web passes downwardly 70

about the roll 10 rotatably mounted in the ends of the bars 51, which bars are rotatably mounted at their midpoints in the frame bracket 52 mounted upon the frame base 53. The ends of the arms 51 opposite the roller 10 carry counterweights 54 for counterbalancing the roller to a greater or less extent. Fixed upon the gudgeon 55 upon each one of the arms 51 and which serves to pivot the arm in the frame, is a spur gear 56 meshing with a spur gear 57 fixed upon the shaft 58 rotatably mounted in the frame bracket 52 and having fixed upon it the hand wheel 59. It will now be apparent that by turning the hand wheel 59 in one direction or the other the arms 51 and roller 10 may be swung in one direction or the other to bear upon the web 2 to a greater or less extent.

From the roller 10 the web passes over the upper side of the coating applying roller 11. This is a second coat of the coating and is a very important feature as surely providing a uniform, smooth and glossy coat. The first coat is quite apt to be uneven or slightly rough because of occluded air, variation in quality or mass or uneven distribution or for other causes. The second coat remedies this and produces an absolutely smooth and uniform coating. The coating for the second coat is carried up by the roller 60 from the heated bath 61 in which it is immersed and hence transferred to the roller 11 which applies the coating to the already first coated surface of the web. The rollers 11 and 60 are similar to the rollers 5 and 27, rotatably mounted and geared together as specified in connection with rollers 5 and 27. Also the rollers 11 and 60 are held spaced apart by springs and the space between the rollers for regulating the thickness of the coating may be regulated by hand wheels 62 and 63 in the same manner and by the same kind of means as set forth in connection with the rollers 5 and 27.

The rollers 60 and 11 are driven from the motor 41 by means of a sprocket chain 64 engaging the sprocket wheels 65 and 66 respectively fixed upon the shafts of the rollers 27 and 60.

From the roller 11 the web proceeds over the convex face of the heated smoothing bar 12 which is constructed and mounted in a precisely similar manner to the smoothing bar 7, has a chromium plated face and is adjustable as to its pressure and contact surface upon the web by means of a hand wheel 65 in precisely the same manner as the smoothing bar 7.

From the smoothing bar 12 the web passes about the roller 13 which is driven from the motor 67. The sprocket wheel 67' fixed on the shaft of the motor is connected by a sprocket chain 68 with a sprocket wheel 69 fixed on the shaft 70 of the roller 13, driving it in the direction as indicated by the arrow.

The rollers 13 and 14 are geared together by the pair of gears 71 so that the roller 14 also is driven in the opposite direction to that of the roller 13.

It will be observed that in passing about the roller 13 the coated side of the web is outward whereby the coating which may be still in a tacky condition is prevented from coming in contact with and sticking to or being wiped off by the roller.

The web in passing about the roller 13 and before it reaches the roller 14 may have its coating set to a sufficient degree, it being observed that the coated side of the web comes against the roller 14, but, if desired, the roller 14 may be

water cooled so that it may be properly set. From the roller 14 the coated web 2 passes to the take-up reel 15.

The roll shaft 15' is driven from a sprocket wheel 72 fixed on the shaft 70 of the roller 13, and connected by a sprocket chain 73 with the sprocket wheel 74 on the shaft 75. The shaft 75 is connected by means of a friction drive 76 with a shaft 77 rotatably mounted in the reel support 78. Also mounted in the reel support 78 is a rotatable shaft 79 geared by means of spur gears 80 to the shaft 77 so that the shaft 79 turns in the opposite direction from that of the shaft 77. The other end of the shaft 15' may be mounted to rotate in a forward bearing 81 on the reel support 82, when it is connected to be driven from the shaft 77 as shown in Fig. 2 or the reel shaft may be mounted in another bearing 83 in line with the shaft 79, when the shaft 15' is adjusted to cooperate with the shaft 79.

A removable bearing cap 84 holds the shaft in position in whichever bearing it may be located, and may be removed to permit the movement of the shaft from one bearing to the other. The end of the reel shaft 15' is provided with a socket portion 85 into which is adapted to be inserted the end of either the shaft 77 or the shaft 79. The end of each of the shafts is made hexagonal or square or some other suitable polygonal shape in cross section, and the socket is made to a corresponding cross section, so that when the end of the shaft is inserted in the socket one cannot turn independently of the other. In the drawings, the shaft 15' is shown as connected in operative relation to the shaft 77. If, however, it is desired to place the shaft 15' in operative relation to the shaft 79 the bearing cap 84 can be removed, the shaft 15' lifted out of the bearing and the socket 85 disconnected from the end of the shaft 77. The shaft 15' is then placed in position where the end of the shaft 79 enters within the socket and the other end of the shaft is placed in the bearing 83. The cap 84 is then applied. Obviously in this manner the reel shaft 15' may be operatively related with either of the shafts 77 or 79 as may be desired, the object being to cause the reel to be turned in either direction desired, it being desirable under some circumstances to change the direction of rotation of the reel.

The friction drive 76 is provided for the purpose of preventing too great tension on the web, if, for any reason, the pull upon the web by the reel exceeds that which is permissible. It may be observed in this connection that the diameter of the web roll upon which the fabric is wound varies with the amount which has been wound on it, and therefore the peripheral speed at the surface of the wound fabric varies greatly, and if provision were not made for slippage by the friction drive the increased speed with the increased diameter of the wound fabric roll would place an undue tension on the web which might rupture it.

A bar 2' extends transversely of the machine beneath, but not touching, the web, the bar 2' being supported in arms 3' rotatably mounted in the sides of the machine frame. This is for the purpose of providing a means for lifting the web 2 off the roll 5 when desired. When the web is stopped the roll 5 is usually continuously running and it would be injurious for the roll to continue running in contact with the web when the latter was stopped. For this reason the bar

2' is provided for lifting the web from the roll. A similar bar 4' passes beneath the web 2 after the roll 11, such bar being mounted in similar arms 5' pivotally mounted in the sides of the machine. This functions to lift the web 2 from the roll 11 when desired by swinging the bar 4' upwardly.

The second coating on the machine of Figure 1 is at a lower temperature than the first coating. While the heat of the second coat will, to some extent, heat up the first coating which has been cooled, nevertheless it is not desired to heat it to such an extent as to destroy its structure.

Referring to Fig. 4, there is therein shown a diagrammatic view of the apparatus whereby laminated and coated sheets may be produced. The web 86 is drawn from the fabric roll 87 and thence passes between the idler rolls 88 and 89 similar to the rolls 3 and 4 of Fig. 1. Thence the web passes over a roller 90 cooperating with another roller 91. The rollers 90 and 91 being heated, the lower one dipping into a molten bath 92 of coating and the rollers cooperating with each other and mounted similarly to the rollers 5 and 21 of Fig. 1.

Coating is thus applied to the under side of the web 86 and the web thence passes over the convex surface of the heated smoothing bar 93 constructed and adjustable like the smoothing bar 7 of Fig. 1. Thence the web passes about a roller 94 corresponding to the roller 8 of Fig. 1 whence the web passes to and about the roller 95 corresponding to the roller 9 of Fig. 1. The web thence passes over a counterweighted idler roll 96 similarly constructed and mounted to the roll 10 of Fig. 1. The web, however, passes outside instead of inside of the roller 96 so as to increase the arc of contact of the web with the heated roller 97 to which the web passes from the roller 96. The roller 97 forms with the roller 98 pressure rolls between which the web 86 passes.

In order to provide a laminated sheet a second web 99 is drawn from the roll 100 and passes about the idler roll 101 which causes an increased area of contact of the web 99 with the heater roller 98. Increasing the arc of contact of the web 99 with the heated roller 98 gives an opportunity for the web to be heated by the roller 98 so as to cause proper cooperation with the coating. Increasing the arc of contact of the web 86 with the roller 97 gives an opportunity for the heat of the roller 97 to heat the coating which has already set upon the web 86 so that it becomes sufficiently soft or tacky to cause the web 86 to be stuck or wedged to the web 99 as the two webs are pressed together in passing between the rolls 97 and 98. Also in passing about the roll 98, the web 99 has applied to its lower side the coating carried up from the melted coated bath 102 by the roll 98 and applied to the web 99.

The web 103 passing from the rolls 97 and 98 to the roller 104 is laminated with the under side coated. The laminated web passes about the roll 104 which is water cooled to cause setting of the coating to securely wed the layers 86 and 99 together and also cause the proper setting of the coating on the lower side of the laminated web. From the roll 104 the laminated web passes to the roll 105 which is so set as to cause a large area of contact of the web with the cooled roll 104 so that the cooling effect may be increased. After passing about the roll 105 the laminated web passes to the take-up roll 106.

The rolls 80, 91, 97, 98, 104 and 105 are driven

and turned in the direction of their respective arrows, the other rolls being idlers.

Instead of the web from the roll 100 passing into contact with the web 86 in the manner and at the stage as specified, to form the laminated sheet, the web may proceed from the roll 100 along the path 99' and about the idler roll 107 which presses the web firmly against the coated side of the web 86 while such coating is warm and tacky, so that the web from the roll 100 is wedged to the web 86, forming the laminated sheet, and such laminated sheet or web then passes about the rollers 95 and 96 to the rollers 97 and 98 whereby a coating from the bath 102 is applied to one face of the laminated web. The web instead of passing above the roll 98, as in Fig. 1, may pass beneath the same and instead of passing between the rollers 97 and 98 may pass over the top of the roller 97 similar to the manner in which the web passes over the roller 11 in Fig. 1, when the rollers 97 and 98 will operate in a similar manner to apply a coating from the bath 102 to the underside of the web.

Coatings which may be suitably employed in the foregoing apparatus are disclosed in the United States Patent No. 2,117,199 Bert C. Miller granted May 10, 1938, such coating being applied by the hot method. It will be understood, however, that other coatings having different ingredients and characteristics may be employed.

What I claim is:

1. In apparatus for coating webs, the combination with a roll adapted to receive coating from a bath, of a second roll spaced from said first-mentioned roll to permit the coating to pass between said rolls whereby said coating is carried from said bath to said second roll and by said second roll to the web and means for passing a web in contact with the coating upon the said second roll, said web contacting the coating on said second roll at a region remote from that where the rolls closest approach each other, the space between said rolls being free for the passage of the coating, means for moving the axis of one roll with relation to the axis of the other roll, a smoothing bar receiving the web from said rolls, a third roll receiving the web from said bar, a fourth roll above said third roll and receiving the web therefrom, a fifth roll at a lower level than, and receiving the web from said fourth roll, means for operating said roll-axis-moving means, the last-mentioned means extending longitudinally of the apparatus into a position longitudinally between said fourth and fifth rolls and remote from said first two mentioned rolls where said last-mentioned means is operable by an operator inspecting the coated web.

2. In apparatus for coating webs, the combination with a roll adapted to receive coating from a bath, of a second roll spaced from said first-mentioned roll to permit the coating to pass between said rolls whereby said coating is carried from said bath to said second roll and by said second roll to the web and means for passing a web in contact with the coating upon the said second roll, said web contacting the coating on said second roll at a region remote from that where the rolls closest approach each other, the space between said rolls being free for the passage of the coating, a smoothing bar, a third roll receiving the web from the smoothing bar, a fourth roll above said third roll and receiving the web from said third roll, a fifth roll at a lower level than, and receiving the web from, said fourth roll and means for moving one end of the

axis of one roll, independently of the other end with relation to the axis of the other roll and operating means for said roll-axis-moving means, said operating means extending longitudinally of the apparatus into a position longitudinally between said fourth and fifth rolls and remote from said first two mentioned rolls where operable by an operator inspecting the coated web.

3. In apparatus for coating webs, the combination with a heated roll, of means for applying coating to said web at said roll, a normally-stationary, heated smoothing-bar acting upon the coated web subsequently to the passage of said roll, a second roll receiving the web from said smoothing bar, a third roll above said second roll and receiving the web from said second roll and a fourth roll at a lower level than, and receiving the web from, said third roll said bar being rotatably mounted, gearing for rotating said bar about its axis and operating means for said gearing extending longitudinally of the apparatus into position longitudinally between said third and fourth rolls and remote from said roll and where operable by an operator inspecting the coated web.

4. Apparatus for coating webs comprising in combination a substantially vertical pair of heated, coating-applying rolls, the lower one of said rolls dipping into a coating bath and said rolls being spaced from each other to permit coat-

ing to pass therebetween, means for driving the lower roll, driving gearing connecting said rolls, a heated smoothing-bar adapted to receive the web from the top of the upper one of said rolls, a roll receiving the web from said smoothing-bar and adapted to hold the web in contact with the upper side of the upper one of said rolls and with said smoothing-bar and a roll above said rolls receiving the web from the last-mentioned roll and raising the coated web into position for ready inspection and to provide a lengthened cooling path for the coated web, a guide roll at a lower level than said web-raising roll and receiving the coated web from the web-raising roll, a second substantially vertical pair of heated coating feed rolls, the lower one of said second pair of rolls dipping into a coating bath and said second pair of rolls being spaced apart to permit the coating to pass therebetween, a heated smoothing-bar adapted to receive the web from the top of the upper one of said second pair of rolls, means for mounting a second guide roll receiving said web from said smoothing-bar, said guide rolls passing said web upon the upper outside of the upper one of said second pair of rolls and also in contact with said smoothing-bar and a third guide roll receiving the web from said second guide roll, said second and third guide rolls in driving relation and means for driving the last-mentioned rolls.

EDWARD PERSON.
